MANUFACTURING COMPANY, OF CLEVELAND, OHIO, A CORPORATION OF OHIO

FAUCET-SUPPORTING PLUG

Application filed February 2, 1929. Serial No. 337,081.

This invention relates to improvements in faucet supporting plugs, and has for its object the provision of a leakproof, cast metal plug for closing a bung opening and integrally supporting a faucet within the associated barrel or drum.

Various types of plugs previously have been provided with faucet supporting means, a typical plug of this type being shown in 10 Patent No. 1,467,698, issued to Owen Thomas.

It has been found that screw plugs having suitable attaching means cast integrally of said plugs are not invariably leakproof with respect to high volatile liquids, particularly, 15 such as gasoline or alcohol. Not infrequently leakage develops through the bodies of the plugs, and more particularly the diaphragm portions thereof. After careful investigation and experiment, I have ascertained that 20 these diaphragm portions have been structurally weakened and rendered relatively porous in a fair percentage of prior cast metal plugs.

Accordingly, I have sought to overcome 25 this difficulty and produce a cheap, yet efficient cast metal plug by so modifying the metallic body or cross section and the attaching means as to avoid cooling stresses and deterioration in the metal of the plug, as will 30 be explained in connection with the accompanying drawings illustrating a preferred type of plug in comparison with one of the prior art. In the attached drawings:

Fig. 1 is a cross section of a screw plug 35 exhibiting the improved faucet attaching means and disposition of the metal in accordance with the instant invention;

Fig. 2 is an exterior plan view thereof;

Fig. 3 is an interior plan view thereof, 40 and

Fig. 4 illustrates the plug with an attached faucet and the container, partially in elevation and partially in section.

Throughout the several figures of the 45 drawings, I have employed the same character of reference to indicate similar parts.

The plug of Fig. 1 is shown sectionally 50 in order to emphasize the features of the invention and assist in explaining the remedied defects of the former types of plug.

Thus, the plug of the prior art is provided with a flanged body portion having a relatively heavy annular cross section exteriorly threaded and interiorly threaded, adapted to screw into the bung opening, and to accommodate the threaded end of a faucet. It will be observed that the diaphragm portion of the plug, becomes weakend and slightly porous or minutely fissured when cooling following casting. It is through this portion, quite apart from the causes of other failures, that the leakage referred to occurs.

Careful investigation has shown that this diaphragm area being surrounded by the much heavier annular portions is subjected to such stresses upon the cooling of the metal, that the diaphragm of the plug is frequently rendered unreliable for retaining the liquid contents of a container against minor leakage, so that accidents from explosion are contributed to, as well as fires.

Referring particularly to Figs. 1 and 3, it will be seen that the annular flanged attaching member body portion *c*, *c*, is of much lighter annular cross section than the construction of the prior art, while the diaphragm *d* comprises a thickened central area *d'* and three adjacent thinner areas *d''*, flanking the lugs *e* separated approximately by 100° arcs. These lugs are of substantial height and are provided with an interrupted thread *e'* for accommodating the threaded end of the faucet, as *f*, Fig. 4.

This radical distribution of the metal and separation of the faucet-supporting lugs permits the casting of screw plugs which safely may be used to displace the present forged plugs of the art, with a material attendant saving. It is found that the diaphragm portion, *d'*, *d''*, of my improved screw plug is not unduly stressed in casting and cooling; particularly as the heavy surrounding annular portion above the flange is dispensed with, while even better attaching means are provided for the faucet.

It should be understood that modifications may be made in the structure exemplifying my improvement and specifically described and shown herein, without departing from my invention as defined in the claims.

Having now described the preferred form of my invention and its principal purpose and advantages, I claim as new, and desire to secure by Letters Patent, the following:

5. 1. In a device of the class described, the combination with a cast metal closure member having an annular attaching member, of faucet-supporting means provided thereon, comprising a plurality of spaced members located within and radially spaced from the annular attaching member, said spaced members having an interrupted thread adapted to receive the threaded end of a faucet.
10. 2. In a device of the class described, the combination with a cast metal screw plug closure member having an annular attaching member, of faucet-supporting means provided upon the inner face of the closure located within and radially spaced from the annular attaching member, said supporting means comprising a set of separated lugs circularly disposed and jointly provided with an interrupted thread adapted temporarily to support the threaded end of a faucet.
15. 3. In a device of the class described, the combination with a cast metal screw plug having an outer threaded rim, a centrally thickened diaphragm and sealing flange, of faucet-supporting means provided upon the inner face of the diaphragm located within and radially spaced from the outer threaded rim, said supporting means comprising a set of circularly disposed lugs jointly provided with an interrupted thread adapted temporarily to support the threaded end of a faucet.
20. 4. In a device of the class described, the combination with a cast metal screw plug having an externally threaded annular rim, a diaphragm of reduced cross section adjacent to the rim and a sealing flange, of circularly disposed lugs upon the diaphragm located within and radially spaced from the rim and from each other and jointly provided with an interrupted thread for temporarily supporting the threaded end of a faucet.
25. 5. In a device of the class described, the combination with a circular cast metal closure member having an annular attaching member and having a central diaphragm of reduced cross section adjacent to its connection with the attaching member, of circularly disposed lugs provided on the diaphragm spaced from each other and from the attaching member and jointly provided with retaining means adapted temporarily to support a faucet.
30. 6. In a device of the class described, the combination with a circular cast metal closure member having an annular attaching member and a diaphragm located centrally of the attaching member having a heavier cross section than the cross section of the attaching member, of a set of spaced circularly disposed lugs provided on the diaphragm, and retain-

ing means on the lugs adapted temporarily to support a faucet.

In testimony whereof I do now affix my signature.

ISAAC T. KAHN.
